HOLDER FOR IRONING BOARD COVERS

William McCrory, Los Angeles, Calif.

Application October 14, 1944, Serial No. 558,677

1 Claim. (Cl. 38—140)

1

This invention relates in general to ironing boards but more particularly to means attachable to at least the opposite edges of a domestic ironing board of a tensioned band for holding a cloth cover and pad detachably and adjustably on the board.

I am aware that patents have been heretofore granted for devices which are in some respects similar to my improvements, at least generally considered, but it is an object of the present to provide a simplified cloth and pad attaching and supporting means which may be with equal effect applied to new as well as old ironing boards.

It is well known that domestic ironing boards are usually covered with a soft pad and a cloth covering applied over the pad which is sewed, pinned or otherwise permanently secured in position over the top, edges and at least a part of the bottom of an ironing board. An object of my invention is to provide a single piece of tensioned metal band of flat cross section bent intermediate at its ends so as to provide a hand grip and pivotally held at its ends as by means of screws, bolts or pins attached at transversely opposite points to the lateral edges of the board in positions near the head end of the board. Thus, the tensioned band may be swung into and out of operative position whereat the opposite legs of the band frictionally clamp the marginal portions of the cloth and pad in position on the board for use.

A further object is to either form the lateral edges of the ironing board with a narrow ledge from the head to the foot of the board, or to apply cleats, brackets or other devices to the edges or bottom of the board so as to extend laterally to a sufficient extent for the purpose of providing supports for the legs of the band when the band is clamped in operating position. Still other objects may appear as the description of my improvement progresses.

I have shown a preferred form of ironing board and cloth clamping attachment therefor in the accompanying drawing, but it will be understood that I conceive it to be possible to modify the structure within the scope of the appended claim without departing from the spirit of my invention. In said drawing:

Fig. 1 is a plan view of an ironing board with my improved cloth attaching means shown thereon in clamping position;

Fig. 2 is a side elevation of the same;

Fig. 3 is a cross sectional view of the same on line 3—3 of Fig. 2; and

Figs. 4 and 5 are cross sectional views similar

2

to Fig. 3 but not necessarily in the plane of line 3—3, showing two different forms of means for supporting the tensioning band on the board, in addition to the form shown in Fig. 3.

5 In its simplest and preferred form the structure shown includes an ironing board A of usual domestic size and shape with a full width head portion 1 and a narrowed foot portion 2 on which I mount a frictional tensioned band B which is preferably of steel but not necessarily so. Band B has a central arcuate bend 3 and legs 4 and 5 of similar length and form adapted to engage the lateral edges 6 and 7, respectively, of board A while the intermediate arcuate portion 3 is disposed at the foot of the board and is extended substantially from the foot edge 8 so as to provide a hand grip by means of which the band B may be held for raising the band from and lowering it into operative position on the board. 10 Said band is pivotally attached to the lateral edges 6 and 7 of the board at transversely opposite points 9 and 10, respectively, as by means of screws, bolts or pins, near the head end of the board. Thus, the band, as indicated in broken 15 lines in Fig. 2, may be lifted and swung in the direction of the head of the board and usually to a position over the center of the screws 9 and 10, in order that a cloth covering C which may readily spread over a soft pad C' and the top of the board A with its lateral marginal portions 11 turned downwardly over the edges 6 and 7 and beneath the legs 4 and 5 of band B, the lateral margins C₂ and end margins C₃ being slightly inward of the adjacent margins of board A, as 20 shown in Figs. 1, 3, 4 and 5.

25 As shown in Fig. 3, board A may be formed with longitudinal ledges 12 and 13 extended outwardly from the edges 6 and 7 but not necessarily around the ends of the board, and thereby 30 forming supports for the band legs 4 and 5, respectively, and the marginal portions 11 of cover C which are held between the bottom edges of the band legs and the upper surfaces of said ledges. The legs 4 and 5 of the band are preferably bowed 35 inwardly in the direction of each other (as at 4' and 5') for the purpose of increasing the tension of the legs as well as the friction applied to the cloth cover C for clamping the cover in position against the edges of the board A. In 40 addition, however, I provide a pair of transversely opposite fixtures D, D, which may be employed in connection with the ledges 12 as shown in Fig. 3 or in the absence of said ledges, as shown in Figure 4. Said fixtures have arms 14 attached 45 as by means of screws 15 to the bottom of board

A and substantially right angularly disposed up-standing arms 16 which may be slightly bowed as shown and frictionally engage the outer sides of the legs 4 and 5 of the band B or the cover margins 11, as the case may be. Thus, fixtures D, D cooperate with the ledge 12 to support and frictionally hold the band in cover clamping position, as in Fig. 3, and to likewise support and hold the band in the absence of ledge 12, as in Fig. 4.

In addition to the fixtures D and frequently in the absence of said fixtures, cleats E, E, may be affixed to the bottom of the board, as shown in Fig. 5, which extends outwardly from the lateral edges of the board and underlie the legs of band B, said cleats being attached as by means of screws 16 to the board.

I claim:

A holder for ironing board covers having strips pivoted at its ends to opposite sides of the back end of the board, and adapted to be swung downwardly to clamp the edge of the cloth around the periphery of the board, comprising: a single loop of resilient material providing a self-tensioning clamp having longitudinally extending portions inwardly bowed in open position so that in closed position the longitudinally extending portions will stretch the cloth cross the board and clamp

it firmly against the board; and outer end portions sloping inwardly from the longitudinal portions and connected by an arcuate portion serving to resiliently urge said outer sloping portions to engage with the outer end edges of the board.

5 WILLIAM McCRRORY.
